UNITED STATES PATENT OFFICE.

LOUIS J. SOLBERG, OF MALTA, MONTANA.

FOLDING CLAMP.

1,310,551.

Specification of Letters Patent. Patented July 22, 1919.

Application filed May 17, 1918. Serial No. 235,151.

To all whom it may concern:

Be it known that I, LOUIS J. SOLBERG, a citizen of the United States, residing at Malta, in the county of Phillips and State of Montana, have invented certain new and useful Improvements in Folding Clamps; and I do hereby declare the following to be a full, clear, and exact description of the invention, such as will enable others skilled in the art to which it appertains to make and use the same.

My invention has for its object to provide an extremely simple and highly efficient clamp intended for general use, but especially adapted for holding parts of a harness while stitching the same.

To the above end, generally stated, the invention consists of the novel devices and combinations of devices hereinafter described and defined in the claims.

In the accompanying drawings, which illustrate the invention, like characters indicate like parts throughout the several views.

Referring to the drawings, Figure 1 is a view illustrating the improved clamp in an operative position by means of full lines and in a folded position by means of broken lines; and

Fig. 2 is a side elevation of the improved clamp, as illustrated by means of full lines in Fig. 1.

The numeral 3 indicates a pair of flat base members connected by a hinge 4 in a manner to permit said members to be spread out flat end to end, or folded, one upon the other, as shown in Fig. 1. A pair of jaws 5 is connected, one to each of the base members 3 by hinges 6. These hinges 6 connect the jaws 5 to the base members 3, outward of their inner ends, in a manner to permit said jaws to be set in converging operative positions, or folded outward into flat engagement with the respective base members, as shown in Fig. 1.

A thumb nut-equipped draw bolt 7 is inserted through a pair of alined bores in the jaws 5, for drawing said jaws together, as shown in Fig. 1, or upon the work held therebetween. In this position of the jaws 5, washers 8 are preferably applied to the draw bolt 7 under the head and nut thereof. In the outer face of each jaw 5, is a shallow rectangular box-holding recess 9 located outward of the bolt 7. The jaws 5 are somewhat longer than the base members 3 and

when folded thereupon, owing to their hinged relation thereto, bring the box-holding recesses 9 outward of the outer ends of said base members.

Formed in each base member 3, outward of the respective hinge 6, is a rectangular transverse opening 10. These openings 10, when the base members 3 are folded, one upon the other, are alined to afford a receptacle that is closed by the jaws 5, when folded onto said base members. Also formed in each base member 3, outward of the respective opening 10, is a bore 11, that is alined with the bores in the jaws 3 when said jaws are folded upon the base members, to receive the draw bolt 7, and thereby hold the clamp folded, as shown by dotted lines in Fig. 1. An open box 12 is placed between the jaws 5, when folded, with its bottom and upper edges seated within the recesses 9. Obviously, one of the jaws 3 affords a cover for the box 12 and the other thereof holds said box thereagainst, while the recesses 9 securely hold the box against endwise or lateral movements, with respect to the jaws.

As previously stated, the improved folding clamp is especially adapted for use in holding parts of a harness while stitching the same. In this use of the clamp, the operator may firmly and securely hold the clamp in a convenient position for his work by sitting upon a chair or bench with the jaws of the clamp projecting upward between his legs and with the outer projecting end portions of the base members 3. The receptacle 10—10 and box 12 may be used for holding tools, rivets, etc.

What I claim is:—

1. A folding clamp comprising a pair of hinge-connected base members, a pair of co-operating jaws hinged, one to each of the base members, and means for securing the jaws in operative positions, the jaws when in operative positions being adapted to hold the base members against folding movement.

2. A folding clamp comprising a pair of hinge-connected base members adapted to be folded, one upon the other, a pair of co-operating jaws hinged, one to each of the base members and adapted to be folded onto the respective base members, and a draw bolt connecting the jaws, each of said base members having a transverse opening, said openings arranged to be brought into alinement, when the base members are folded one

upon the other, to afford a receptacle that is closed by the jaws when folded onto the respective base members.

3. A folding clamp comprising a pair of hinge-connected base members, a pair of co-operating jaws hinged, one to each of the base members, and a draw bolt connecting the jaws and extending through alined bores formed therein, each of said base members

10. having a bore that is alined with the bores in the jaws, when the clamp is folded, to receive the draw bolt for holding said clamp folded.

4. A folding clamp comprising a pair of hinge-connected base members arranged to be folded, one upon the other, a pair of co-operating jaws hinged, one to each of the base members and arranged to be folded thereupon, and means for securing the jaws

20. in operative positions.

5. A folding clamp comprising a pair of hinge-connected base members adapted to be folded one upon the other, a pair of co-operating jaws hinged, one to each of the base members and adapted to be folded onto the respective base members, and a draw bolt connecting the jaws and extending through alined bores formed therein, each of said base members having a transverse

25. opening, said openings arranged to be brought into alinement, when the base members are folded one upon the other, to afford

a receptacle that is closed by the jaws when folded onto the respective base members, each of said base members having a bore

35. that is alined with the bores in the jaws when the clamp is folded to receive the draw bolt and thereby hold said clamp folded.

6. A folding clamp comprising a pair of hinge-connected base members, each having

40. a transverse opening and arranged to be folded, one upon the other, a pair of co-operating jaws hinged, one to each of the members and arranged to be folded upon the respective base members, said openings

45. arranged to be brought into alinement when the base members are folded, one upon the other, to afford a receptacle that is closed by the jaws when folded onto the respective base members and means for securing the

50. jaws in either operative or folded position.

7. A folding clamp comprising a pair of hinge-connected base members, a pair of co-operating jaws hinged, one to the intermediate portion of each of the base members, and means for securing the jaws in

55. operative position.

In testimony whereof I affix my signature in presence of two witnesses.

LOUIS J. SOLBERG.
